UNITED STATES PATENT OFFICE

2,504,236

MECHANISM FOR REMOVING STACKED ARTICLES FROM A CHAMBER

James E. Underwood, Oakmont, Pa., assignor to
Aluminum Company of America, Pittsburgh,
Pa., a corporation of Pennsylvania

Application May 20, 1944, Serial No. 536,490,
which is a division of application Serial No.
482,739, April 12, 1943. Divided and this applica-
tion February 17, 1945, Serial No. 578,480

4 Claims. (Cl. 214—8.5)

1

This invention relates to improvements in machines of the class adapted to assemble a disc, wafer, washer or other shape made of relatively thin or pliable material with a receiving member. The invention forming the subject matter of the present application is directed specifically to the problems attendant upon accurate and rapid delivery of cup-like or tubular articles properly oriented for assembly of other articles therewith, this subject matter having been divided from my copending application Serial No. 536,490, filed May 20, 1944, and now abandoned, which latter application is, in turn, a division of my copending application Serial No. 482,739, filed April 12, 1943, now United States Patent No. 2,405,074 issued July 30, 1946.

Machines which are the general subject of my original application are those which will operate continuously at high speed to perform an assembling operation; which will accurately and positively handle thin, wafer-like parts; which will accurately and positively handle relatively heavier parts of different or the same shape; which will maintain a constant flow to the point of assembly of the parts to be assembled; which will bring all parts to the point of assembly in proper position and will there accurately position the parts with respect to each other; which will perform operations on the assembly to unite or otherwise permanently establish the assembled relationship. The general object of this invention is the provision in such a machine of an improved article handling system adapted to present to a work station a flow of cup-like or tubular articles established and maintained in a predetermined oriented position.

Fig. 1 is a side view of a machine illustrating one type of machine in which the improved mechanism of this invention may be embodied.

Fig. 2 is a vertical section taken through a portion of a handling and feeding mechanism embodying the principles of this invention, said handling and feeding mechanism being generally designated in Fig. 1 as 26, 27.

Fig. 3 is a vertical sectional view taken at line 3—3 as indicated on Fig. 2.

Fig. 4 is a view taken as indicated on section line 4—4 shown in Fig. 1, the view showing the assembly 27 in cross section and the assembly 30 in top plan view.

Fig. 5 is a vertical sectional view of the part shown in Fig. 4 taken at line 5—5 indicated on Fig. 4 and also including, to the left thereof, a portion of cross sectional view through the part generally designated as 28 in Fig. 1.

2

Fig. 6 is a view of the lower portion of the handling and feeding mechanism taken as indicated by lines 6—6 on Fig. 5.

Fig. 7 is a further sectional view of a portion of the elements shown in Fig. 5 illustrating one position of said elements during their cooperating movement.

Fig. 8 is a cross section through a detonator cup such as may be subjected to the handling operation herein specifically described.

The general organization of the machine is best shown by Fig. 1. The machine is carried by a frame most parts of which are generally indicated by the numeral 21. Mounted on this frame is the article handling system consisting of a hopper 23 mounted on post 22, a transfer tube 24, a turning mechanism 26, a chute mechanism 27, and a transfer slide assembly 30. A work translating means such as turret 28, actuated by Geneva drive 29, is adapted to receive work at turret station A and to present it to various assembly operations at stations B and C. A foil supply and feed system includes supply reel 31 from which the foil 32 travels over rollers 33, 34 and 35 through foil feed mechanism 36 over roller 25 to rewind reel 37. Mounted above turret 28 at station B is the die and punch assembly 38. Mounted at station C is the hot punch assembly 39. Leading from the bottom position of the turret are transfer tubes 40 which deliver finished assemblies from that station to inspection unit 41, which preferably is of a type in which a defective assembly will admit air to destroy a vacuum to render article removing means ineffective so that proper and defective assemblies may be removed from the unit at different points.

The detailed operation of the machine shown in Fig. 1 and the driving elements by which its parts are suitably coordinated are described in detail in the aforesaid United States Patent No. 2,405,074 and are not further mentioned here except to the extent necessary to specifically illustrate the operation and utility of the improved handling and feeding mechanism to which this present invention is directed. In amplification of what has been stated above it may, however, be noted that articles delivered through the handling and feeding system generally designated at 23, 24, 26 and 27 are delivered by a transfer mechanism 30 to position A in the turret 28 and upon continued operation of the machine are indexed to position B where a thin wafer is cut from foil 32 and assembled with the article by reason of the action of die and punch assembly 38. Thereafter the assembled article

is indexed to station C where a hot punch assembly 39 completes the operation, and thence indexed to a discharge station where the finally assembled article is fed through the tube 40 to an inspection machine 41. While the machine thus generally illustrated is one to which the use of the present invention is particularly adapted, it will be apparent from the following description that the present invention may be used wherever a series of oriented articles is to be successively delivered to an article assembling or handling operation.

In operation of machines of the type to which this invention generally relates and which is illustrated by the machine shown in Fig. 1 it is necessary that the articles which are to be handled must be selected and oriented from a large mass of such articles and thereafter delivered in a constant flow to the work operation, in the illustrated case to the work translating turret 28 at station A. The first step in the process of delivery of these articles is to assemble a mass of the same in a device such as the hopper 23, which device may contain any selecting mechanism as may be suitable, such as that shown in United States Patent No. 1,232,893 to E. R. Candee, which will select single articles from an unoriented mass thereof, orient the articles and start them in continued flow in oriented position. In the device shown the single articles so oriented are fed from the hopper into transfer tube 24 and thence to a turning mechanism 26.

Thus, oriented detonator cups entering transfer tube 24 fall therethrough by gravity, their partially closed ends forward, to the floor of the turning mechanism 26, the details of which are best shown at Figs. 2 and 3. The turning mechanism, positioned between the hopper 23 and chute mechanism 27, provides for feeding the endwise-falling detonator cups into transfer slot 75 in a sidewise position. For that purpose the turning mechanism consists of a wheel 76 fixed upon a shaft 77 which is rotated by means of pulley 82 fixed on the end thereof. Carried by wheel 76 are fingers 78 which are yieldingly, but firmly, held by springs 79 against the floor 84 of the circular chamber. The housing plates 85 are cut to form a slot 75 leading from its aperture in the floor of the transfer chamber to the multiple chute chamber 86. The detonator cups, having been oriented in the hopper 23 and delivered to transfer tube 24 in oriented position with their closed ends forward, pass through that tube in end-to-end position, the shape and size of the tube 24 being such as to maintain an end-to-end flow. They are thus singly delivered to the floor 84 of the transfer chamber where the housing plate 85 provides an abutment to limit the forward motion of each cup as it frees itself of the transfer tube 24 and thus leave the cup on the floor at the position X indicated in Fig. 2. In this position the cup lies across the travel of members 78 each of which has an end portion shaped to receive the cup. The outlet from the chamber to passage 75 affords means positioned in the path of travel of the fingers 78 to receive and remove the cups from the chamber as they are swept across the floor by said fingers, and said passage 75 and chamber 86 are so proportioned as to maintain the cups in the side-by-side relationship established by their flow through this aperture. Thus, the end-to-end flow of the cups originally established in tube 24 is terminated and the flow reestablished in side-

by-side position without, however, change in the orientation of the cups originally fixed by the selector hopper to present the perforate bottom of the cup toward the station to which the cups are traveling. The bottom portion of multiple chute chamber 86 is divided, as shown in Figs. 2 and 4 but best shown in Fig. 6, into a plurality of cup feeding passages by the dividers or fingers 87, 87'. Each of said passages terminates at a fixed position 88. The detonator cups fall into the chamber 86 from where they pass into the cup feeding slots, the lower cup in each slot lying in the terminus position 88. Fingers 87 are carried upon cross bar 89 while the fingers 87' are carried upon cross bar 89'. These cross bars are mounted on housing plate 85 for vertical movement with respect thereto, and the end of each cross bar is provided with a roller 90. The cross bars are held together in normal position through the medium of spring loaded bolts 91. The cross bar rollers 90 are so arranged that a wedge or pin, such as agitator pin 92, forced between said rollers, will separate the cross bars against the action of the springs on bolts 91 thus moving fingers 87' apart from fingers 87 and imparting movement to the mass of cups lying in the chamber 86, which movement facilitates passage of the cups into the cup-feeding slots. The cups, lying the bottom of the cup-feeding slots in position to be fed to the turret mechanism, present their closed ends 12 toward the turret 28 at turret position A, this orientation of the cups having been achieved by the turning means above described, which, while changing the downward travel of the cup from an endwise fall to a sidewise fall, does not disturb the relative end-to-end position of the cup originally established on delivery to transfer tube 24.

The turret 28 has positioned on its periphery a number of cup-receiving chucks 93 in each of which are provided the cup-receiving apertures 94 (as best shown in Fig. 7). When a chuck 93 is presented at turret station A these apertures have the same axes as the termini 88 of the cup slots which lie at the bottom of the chamber 86. Cups are periodically transferred from their position at termini 88 to the apertures 94 of a turret chuck 93 by the transfer slide assembly 30.

Transfer assembly 30, shown at Figs. 1 and 7, but best shown at Figs. 4 and 5, consists of a carriage 95 mounted on frame 21 for periodic translation toward and away from turret station A. Rods 96 corresponding in axial position and number to cup chute termini 88 and to turret chuck apertures 94 are mounted in said carriage. Each such rod consists of a forwardly extended portion and a rearwardly extending portion and of a slide bearing portion 97 which latter is positioned in rod chamber 98 and normally held at one end thereof by springs 99. Mounted on the carriage is bracket 100 which carries the agitator pins 92, whose function, as above described, is to pass between rollers 90 and cause separation of the cross bars which carry fingers 87 and 87' in the multiple chute assembly. The ends of these pins 92 are notched, as shown at 101, to agitate the rollers as they pass therebetween, thus imparting a jerking movement to the cross bars and the fingers attached thereto. Likewise mounted on transfer slide carriage 95 by means of brackets 102 and pin 103 is the pivoted arm 104 which is normally positioned, by action of spring 105 as shown in Fig. 5, to place its downwardly extending portion 106 directly behind the rearward ends 75 of the pins 96. Mounted separately of the assem-

bly 30 and on fixed bracket 107 is switch 108 which carries switch arm 109 on switch shaft 110. Switch arm roller 111 is adapted to be contacted by the surface 112 of the arm 104 when it is raised against the action of the spring 105.

In its normal cycle, the transfer slide assembly 30 going forward from the position shown at Fig. 5 to the position shown at Fig. 7 brings its rods 96 through apertures in the chute housing into the cups 10 which lie in termini 88. Under continued forward motion the rods contact the semi-closed ends 12 of said cups and carry the cups through apertures 141 into the cup-receiving apertures 94 of that chuck 93 which is, at that moment, positioned at turret station A. Simultaneously the agitator pins 92 passing through the apertures 113 in the multiple chute housing 85 contact and pass between the rollers 90 thus causing relative movement of fingers 87 and 87', as above described, and facilitating movement of the cups into the cup slots therebetween. At the end of this operation the transfer slide assembly is again returned by linkage 72 to its original starting position from where the cycle is again repeated as the next chuck 93 is indexed at turret station A. If a cup lying in a cup chute terminus 88 is bent or otherwise damaged or is wrongly positioned so as to prevent the free passage thereto of a transfer rod 96, the rod yields backwardly against the action of spring 99 until its rearward portion contacts the downwardly extending portion 106 of the arm 104 thus raising the arm into contact with the roller of the switch arm 109 and tripping the switch 108 to stop the machine and allow removal of the offending cup.

It will be apparent from the foregoing description that the invention therein described and hereafter claimed may be embodied in machines and methods for performing assembly operations other than those specifically shown and described, and that the construction of the various parts may be varied without departing from the invention as defined in the appended claims.

I claim:

1. In an article handling mechanism, a chamber for receiving articles, means located in the lower portion of said chamber to divide the same into a number of article receiving passageways each terminating at a predetermined point, said dividing means comprising a plurality of dividers, at least some of which are mounted for movement parallel to said passageways and a device adapted to periodically remove articles positioned in the terminals of said passageways, said device including means adapted to impart the said movement to the dividers during the removal operation.

2. In an article handling mechanism, a chamber for receiving articles, means located in the

lower portion of said chamber to divide the same into a number of article receiving passageways, each terminating at a predetermined point, said dividing means comprising a plurality of dividers, at least some of which are mounted for longitudinal movement parallel to said passageways, each divider being carried on one of several cross bars, the ends of each cross bar being provided with rollers, said cross bars being held in close parallel relationship by spring means, agitator pins mounted on means to periodically pass said agitator pins between the rollers of said cross bars and a device adapted to periodically remove articles seated at the terminals of each passageway.

3. In an article handling mechanism, a chamber for receiving articles, means located in the lower portion of said chamber to divide the same into a number of article receiving passageways, each terminating at a predetermined point, said dividing means comprising a plurality of dividers, at least some of which are fixedly mounted on means yieldingly held in a normal position, a device adapted for periodic movement to remove articles seated at the terminal of each passageway and means operable during the movement of said device to momentarily displace said movable means out of original position, whereby the dividers fixed to said movable means are momentarily displaced from normal position in a direction parallel to said passageways.

4. In an article handling mechanism, a chamber for receiving articles, means located in the lower portion of said chamber to divide the same into a number of article receiving passageways, each terminating at a predetermined point, said dividing means comprising a plurality of dividers, at least some of which are mounted for longitudinal movement parallel to said passageways and are fixed upon and carried by a movable bar yieldingly held in normal position, bar contact means operably mounted to periodically contact said bar to move the same from said normal position and means adapted to periodically move articles seated at the terminals of each passageway.
